BENDING TOOL

Filed Dec. 5, 1929

Attorney

UNITED STATES PATENT OFFICE

RUDOLPH C. PARATSCHEK, OF TOLEDO, OHIO

BENDING TOOL

Application filed December 5, 1929. Serial No. 411,744.

This invention relates to bending of lengths of stock.

This invention has utility as a bending device for electric conduit metallic tubing.

5 Referring to the drawings:

Fig. 1 is a view of an embodiment of the invention as a bending device for a metallic conduit;

10 Fig. 2 is a section on the line II—II, Fig. 1, looking in the direction of the arrow;

Fig. 3 is a section on the line III—III, Fig. 1;

Fig. 4 is a section on the line IV—IV, Fig. 2; and

15 Fig. 5 is a modification of the device.

The tool comprises a head having a convex arcuate face 14 of the desired curve, and an open groove or channel in said face constituting a seat for the work and terminating at 20 one end in a closed loop or terminus 3, the base of which is expanded at its outer end to provide a clearance at 4. The depth of the groove or channel is equal to the diameter of the work to be bent so that its arcuate edges

25 may be flush with the outer side of the work.

Tubular conduit 1 is placed on support as cement floor 2, after the operator has thrust the conduit 1 through seat terminus 3 of the tool to the desired point of clearance for the 30 stock beyond the bend and with the stock extending from the seat 3 with clearance 4 on the side remote from the support 2.

The seat 3 has taper portion 5 to opening 6 of channel form having concave root 7 and 35 side flanges 8 of a proportion to be just flush with the stock 1. This channel seat or groove is of arc form extending from the terminal seat 3 and having at its remote terminal a ledge 9 as a footrest. Intermediate the extent 40 of this tool, externally threaded boss 10 is in position for mounting thereon internally threaded element 11 thereby to extend radially medially the extent of this arc shaped seat of the bender.

45 In operation, after thrusting the stock 1 through the seat 3, as permitted by clearance 4, the bevel portion 5 is in position against the support 2 and the operator with one foot 12 to hold the stock against the support 2 as 50 remote from the tool, will press his other foot

13 on the ledge 9 as away from the support and in Fig. 1, swing the handle 11 counter-clockwise as assisted by the pressure of foot 13 on the ledge 9 in riding the stock 1 along into the channel 7, 8, on the pair of outer 55 edges 14 of the channel as a rolling fulcrum. The dimension of this channel is such that with the stock flush therewith and of the transverse dimension of the stock 1, the stock is nicely re-formed into an arc of the radius 60 of this tool, which in practice say for $\frac{3}{4}$ " conduit may be a 4" radius of 90° extent. This means that the tool may be definitely used for a desired contour and dimension of arc, either greater or less angular extent than the tool 65 itself, for the tool thus may operate for the 90° bend in the full swing and in less than the full swing in less degree, while a full shifting may be had in make up to return 70 bends or circles as desired.

It is important that the outer side of the stock be flush with the outer faces of the flanges forming the rolling fulcrum, because if the stock projects radially beyond the flanges the thrust downward on the fulcrum 75 would tend to flatten the stock, while if the flanges project beyond the outer face of the stock, the stock will not be held to the inner bending surface of the seat so that improper deformation may follow.

In Fig. 5 lateral way 15 is provided so that when the stock is of considerable length or has terminal fittings thereon, the tool may be placed in position with the stock laterally of the stock intermediate its length and thereafter used as hereinbefore set forth.

What is claimed and it is desired to secure by United States Letters Patent is:

1. For the bending of stock, a tool having a seat of a form to be approached with the stock 90 as lineally protruding therefrom, there to be held against a support, said tool having a ledge terminal of said seat to be held for positioning the tool against the same support as the stock, said tool from a remote terminal 95 of said seat to the ledge terminal having a channel with its side walls providing a rolling fulcrum flush with the stock, and an operating handle for rocking the tool on said fulcrum in holding the tool against said support 100

for rocking the stock along in the seat and thereby bending the stock.

2. A portable hand operated conduit bending tool having a loop or terminus for engaging a supported side of the conduit, and a channel former or seat therefrom open toward said support, said channel former sides being approximately flush with the conduit, and an operating handle for rocking the tool on said sides as a rolling fulcrum.
3. A portable hand operated bending tool comprising a channel arc seat with its side extending radially sufficiently to provide a rolling fulcrum coincident with the outer surface of the curve to be bent, and an operating handle protruding radially from said seat.

In witness whereof I affix my signature.

RUDOLPH C. PARATSCHEK.
